UNITED STATES PATENT OFFICE

2,075,241

VALVE PULLING DEVICE

Lester O. Thompson, Oklahoma City, Okla.

Application October 28, 1935, Serial No. 47,120

4 Claims. (Cl. 294—86)

My invention relates to a device for pulling foot-valve mechanism in reciprocating pumps, and more particularly to such mechanism for use in oil well pumps.

5 The prime object of the invention is to provide a positive means for engaging and disengaging selectively a substantially cylindrical concealed object from a point remotely located.

At the present time it is common practice in 10 pumping deep wells, particularly oil wells, to provide a stationary pump barrel in the well below the level of the well fluid, a string of production tubing connected to the barrel and extending therefrom to the earth's surface, to provide a foot-15 valve in the bottom of the barrel, and also a pump-piston reciprocatably mounted in the barrel above the foot-valve, the piston being operated by movement of a string of sucker-rods or pump-rods which extend from the piston to the 20 earth's surface within the production tubing.

In order to avoid the necessity of first removing the string of sucker-rods and afterward the string of production tubing and the pump barrel when it is desired to replace a worn or damaged 25 valve, it has become common practice to removably anchor the foot-valve structure in the barrel in such a manner that it can be engaged by a fishing tool and removed for replacement after the sucker-rod string and the pump-piston has 30 first been removed. The operation now consists of pulling the string of sucker-rods and the pump piston, placing a fishing tool upon the lower end of the lower section of sucker-rod in place of the pump-piston, going back into the well with 35 the string and the fishing tool to engage the foot-valve mechanism, and then re-pulling the sucker-rod string.

The expedient of providing the removable foot-valve, eliminated the necessity of pulling the 40 string of production tubing each time it was desired to remove the foot-valve, but caused the running a sucker-rod string an extra time in order to fish for the foot-valve.

When it is considered that, in deep wells, the 45 operation of pulling the production tubing entailed considerable labor and loss of production, and that the sucker-rod string could be pulled and again lowered an extra time at less expense, it may be seen that the removable foot-valve accomplished a considerable saving of expense over 50 the old method.

My device is designed to eliminate the necessity of running the string into the well the second time in fishing for the foot-valve.

55 This result is accomplished by providing the

upper end of the foot-valve mechanism and the lower end of the pump-piston with complementary structure whereby the two may be positively engaged or disengaged selectively from a point located at the earth's surface, and which at the same time will not interfere with the normal function of either.

Other objects of the present invention are to provide a device of the class described which is new, novel, practical and of utility; which is not only positive in action, but is simple in construction and cheap to manufacture; which may be operated by the mere rotation of the sucker-rod string; which will be durable; and, which will be efficient in accomplishing all of the purposes 15 for which it is intended.

With these and other objects in view as will more fully appear hereinbelow, my invention consists in the construction, novel features, and combination of parts hereinafter more fully described, 20 pointed out in the claims hereto appended, and illustrated in the accompanying one-sheet drawing, of which,

Figure 1 is a fragmentary elevational sectional view of the device operatively installed within a 25 pump barrel;

Figure 2 is a perspective view of the upper tubular element of the device which is shown inverted; and,

Figure 3 is a perspective view of the lower 30 tubular element.

Like characters of reference designate like parts in all the figures.

It is understood that various changes in the form, proportion, size, shape, weight and other 35 details of construction, within the scope of my invention may be resorted to without departing from the spirit or broad principle of my invention and without sacrificing any of the advantages thereof; and it is also understood that the 40 drawing is to be interpreted as being illustrative and not restrictive.

The inventive idea involved is capable of receiving a variety of mechanical expressions one of which, for the purpose of illustrating the invention, is shown in the accompanying drawing wherein:—The reference numeral 1 indicates as a whole a usual pump barrel having a foot-valve structure disposed removably in its lower end. The foot-valve structure consists of a hollow cage 50 2 having a ball valve 3 therein and is not a part of the present invention. However, for a purpose more fully described hereinbelow I provide the upper end portion of the cage with spaced longitudinally extending grooves 4. 55

Positioned within the pump barrel and attached by threads 5 to the lower end of a pump-piston 6 is a substantially tubular element 7 which is the upper member of my device. The interior 5 of the element 7 is provided with spaced grooves 8 which act as ball races for receiving bearing balls 9.

The lower element of the device is indicated by the reference numeral 10 and is of tubular 10 form having a reduced upstanding portion 11 which is adapted to fit snugly and rotatively within the lower end of the upper element 7. The exterior of the upstanding portion 11 is provided with ball race grooves 12 which are spaced apart 15 to correctly register with the previously described grooves 8 within the element 7 when the two elements are in their assembled positions. The balls 9 may be introduced into the races by removal of screws 13 which close lateral bores 20 leading into the grooves through the wall of the element 7. An annular shoulder 14 is formed around the upper end of the element 10 and receives an annular washer 15 of resilient packing material. A similar washer 16 is also provided in a groove 17 which surrounds the lower 25 end of the upstanding portion of the element 10. The lower end of the element 10 is equipped with a plurality of depending lugs or tines 18 which are spaced similarly to the spacing of the notches or 30 grooves 4 and which are adapted for engagement therein when the pump-piston is lowered sufficiently.

It may be seen that when the complementary grooves 8 and 12 are filled with the bearing balls 35 9 the two elements 7 and 10 cannot be separated.

The lower end of the element 7 is provided with a hemispherical depression 19. The end is also equipped with a sloping bottomed groove 20 which becomes deeper the farther it extends from the 40 depression 19. The groove 20 does not communicate with the depression 19 but is separated therefrom by a flat surfaced portion 21.

The lower end of the element 7 is also equipped with an abrupt ended arcuate groove 22 which 45 co-acts with a pin 23 carried by the upper surface or shoulder 24 surrounding the upstanding portion 11 thereof. A hole 25 is provided in the shoulder 24 to receive the pin 23 which projects upwardly into the groove 22 of the element 7. The shoulder 24 also has another hole or bore 26 50 which receives a coil spring 27 and a metal ball 28. The ball is forced by the spring into positive engagement with the lower end of the element 7 and is adapted to fit within the depression 19 55 when the member 7 is rotated to the end of its permitted travel in one direction and is adapted to roll upon the bottom surface of the groove 20 as the element is rotated toward the opposite direction. The ball tends to hold the two elements 7 and 10 against inadvertent rotation in either direction by pressure either in the depression 19 or in the bottom of the groove 20.

The two elements 7 and 10 are provided respectively with bores 30 and 31 which are both eccentric with relation to the exterior of the upstanding portion of the element 7, or in other words are eccentric to the axis upon which one element may be rotated with relation to the other. When the elements 7 and 10 are disposed in radial 70 positions with relation to each other in which the ball 28 is seated in the depression 19, the bores 30 and 31 are in alignment with each other, but when either is rotated with relation to the other, the bores are forced out of alignment causing a 75 reduction in the width of the through passage.

As may best be seen in Fig. 1, the upper portion of the bore 30 is slightly enlarged as shown at 32 to form an abrupt annular shoulder 33.

In carrying out my invention I provide the upper end of the previously described foot-valve structure with an upstanding substantially cylindrical shaft 34 having a downwardly faced abrupt annular shoulder 35 adjacent its upper end. The extreme upper end of the shaft 34 may if desired be pointed as indicated at 36 in order to insure its entry into the bottom of the bore 31 of the element 10.

Operation

In operation, the foot-valve structure will be 15 installed in a usual manner within the bottom of the pump-barrel 1. The device will be attached by threads 5 to the lower end of the pump-piston 6, which is operated by a string of sucker-rods, not shown, attached to the upper end of the 20 piston and extending to the earth's surface.

When first installed, the elements 7 and 10 will be in proper radial positions to aline their respective bores with each other.

During the normal operation of the piston, its 25 stroke will be so regulated that the element 10 at no time comes into contact with the shaft 34.

However, when it is desired for any reason to pull the foot-valve, the piston will be lowered, which will cause the shaft 34 to enter the bore 30 31 and pass through the element 10 and into the element 7 a sufficient distance to locate the shoulder 35 on the shaft above the shoulder 33 of the element 7. As this takes place, the projections 18 on the lower end of the element 10 35 will enter the notches 4 of the foot-valve.

The element 7 will next be rotated by rotating the sucker-rod string, which will force the shoulder 33 to impinge the shaft 34 and engage the shoulder 33 beneath the shoulder 35. The sucker-rod string will then be raised and the foot-valve will be raised with the string. The foot-valve may be replaced by reversing the removing operation.

A suitable valve structure 40, shown in dotted lines in Fig. 1 may be provided between the upper end of the element 7 and the lower end of the pump-piston, if desired.

Although I have shown and described the device as used in connection with a pump-piston 50 and a foot-valve, it will be apparent the same principle of operation could be used in other mechanical structures in which it is desired to engage one cylindrical object with another.

Obviously, the invention is susceptible of embodiment in forms other than that which is illustrated in the accompanying drawing and described herein, and applicable for uses and purposes other than as detailed, and I therefore consider as my own all such modifications and adaptations and other uses of the form of the device herein described as fairly fall within the scope of my invention.

Having thus described my invention, what is claimed and desired to be secured by Letters 65 Patent, is:

1. In valve pulling mechanism, the combination with the housing of a foot-valve for wells, and with a pump-rod, of deformations carried by the upper end of the housing, an upstanding outwardly flanged stud carried by the housing, a tubular interiorly shouldered element connected at its upper end to the lower end of the pump-rod, a second tubular element connected to the first element and rotatable with relation there- 75

to upon an axis eccentric with the bores of both elements, and means carried by the lowermost of said elements for engaging said deformations and preventing its rotation with relation to the 5 valve housing, said stud adapted to pass through the lowermost of said elements and into the uppermost element when the lowermost element is in engagement with said housing, whereby independent rotative movement of the upper element 10 acts to dis-align said bores for causing engagement of the shoulder with the flange.

2. In valve pulling mechanism, the combination with the housing of a foot-valve for wells, and with a pump-rod, of castellations carried by 15 the upper end of the housing, an upstanding outwardly flanged stud carried by the housing, a tubular interiorly shouldered element connected at its upper end to the lower end of the pump-rod, a second tubular element connected to the 20 first element and rotatable with relation thereto upon an axis eccentric with the bores of both elements, and depending projections carried by the lowermost of said elements for engaging said castellations and preventing its rotation with 25 relation to the valve housing, said stud adapted to pass through the lowermost of said elements and into the uppermost element when the lowermost element is in engagement with said housing, whereby independent rotative movement of 30 the upper element acts to dis-align said bores for causing engagement of the shoulder with the flange.

3. In valve pulling mechanism, the combination, with the housing of a foot-valve for wells, 35 and with a pump-rod, of deformations carried by

the upper end of the housing, an upstanding outwardly flanged stud carried by the housing, a tubular interiorly shouldered element connected at its upper end to the lower end of the pump-rod, a second tubular element connected to the first element and rotatable with relation thereto upon an axis eccentric with the bores of both elements, and means carried by the lowermost of said elements for engaging said deformations and preventing its rotation with relation to the valve housing, said stud adapted to pass through the lowermost of said elements and into the uppermost element when the lowermost element is in engagement with said housing, whereby rotation of the upper element independently of the lower acts to throw the two bores out of alignment and to reduce the dimension of the through opening thus causing engagement of the shoulder beneath the flange of the stud.

4. In valve pulling mechanism, the combination with a foot-valve housing for wells, said housing having an upstanding headed stud, and with a pump-rod adapted to be reciprocatably mounted within a well above said housing, of a tubular interiorly shouldered element connected at its upper end to the lower end of the pump-rod, a second tubular element connected to the first element and rotatable with relation thereto upon an axis eccentric with the bores of both elements, said elements adapted to be lowered so as to surround said stud whereby independent rotative movement of the upper element with relation to the lower element causes engagement of the shoulder beneath the head of the stud.
